HYDRAULIC CONTROL SYSTEM

Henry George Ferguson, Stow-on-the-Wold, and John M. Chambers, Leamington, Spa, England, and William John Sands, Lisburn, Northern Ireland; said Chambers and said Sands assignors to Harry Ferguson Holdings Limited, Stow-on-the-Wold, England, a British company

Application March 3, 1948, Serial No. 12,884

4 Claims. (Cl. 97—46.07)

1

This invention relates to hydraulic control systems which comprise a source of pressurized fluid, for example, a pump, a load-sustaining or operating device actuatable by fluid from the said source, and valve means whereby the fluid may be caused to be admitted to and exhausted from the device to shift or actuate the load. More especially the invention relates to hydraulic systems of the type as set forth, for example, in the prior United States Letters Patent Nos. 2,118,180 and 2,118,181 of Henry George Ferguson.

In the system as set forth in said patents the control valve is located at the suction side of the pump and, while this arrangement is beneficial in that it avoids continuous pumping of the oil although the pump is continuously driven, it has the disadvantage that when the draft operates the control valve there will be a certain amount of lag before the pump actually begins to raise the implement in cases where the draft has increased, and the implement is to be correctively raised to the predetermined depth or draft. This lag is due to the fact that there is a vacuum inside the pump which has to be filled before there is effective delivery of oil. There is also the further disadvantage that when the control valve has again closed the pump inlet as the implement draft or depth reaches the predetermined value the pump will deliver its contents and will thus actually cause the implement to be raised too much and this may entail a further cycle of depth or draft correction and so on.

An object of the invention is to obviate or mitigate the above disadvantages.

Another object is to provide in a hydraulic system which includes a continuously driven pressure pump, a load-sustaining or actuating device actuatable by pressure fluid from the pump and valve means controlling an admission port on the suction side of the pump and a discharge port whereby the fluid may be caused to be admitted to and exhausted from the device; a vessel for pressure fluid, which is chargeable up to a predetermined pressure from the pump and is connected to provide in the system a reserve supply of fluid under pressure.

In further accordance with the invention, we provide in a tractor a hydraulic control system for automatic depth or draft or position control of implements attached to the tractor which embodies a new and useful combination including a pressure fluid responsive device, for example, a ram, for lifting, lowering and supporting the implement on the tractor, valve means controlling admission and release port means for said device

2

and movable in accordance with the depth of cut of the implement or its position relative to the tractor to admit or release fluid to or from the device respectively as the implement goes deeper or shallower with respect to a desired depth or as the implement moves in either direction away from a predetermined position relatively to the tractor, and means containing fluid under a predetermined pressure for supplying the fluid to said valve means so that on opening thereof there is instantaneous admission of pressure fluid to the device.

More particularly stated, another object of the invention is to provide a new and improved hydraulic control system for an agricultural tractor or the like having a fluid-operable actuating or load-sustaining device for a soil-engaging or agricultural implement to be controlled, valve means movable under the opposed influence of balance means, such as, a spring and the soil pressure or draft on the implement to admit or release fluid to said device automatically to maintain said implement at a predetermined depth or draft, and a source of pressurized fluid which includes a chamber or container for the fluid, a pump or the like for supplying fluid to said chamber and a control member, for example, a valve on the admission side of the pump, which is operable by the pressure in said chamber to put the pump automatically into or out of effective operation to maintain the fluid at a predetermined pressure in said chamber.

While the invention is susceptible of various modifications and alternative constructions, a preferred embodiment has been shown in the drawings and will be herein described in some detail, but it is to be understood that there is no intention to limit the invention to the specific form disclosed, the intention being, on the contrary, to cover all modifications and alternative constructions falling within the spirit and scope of the invention as expressed in the appended claims.

Fig. 1 is an elevation of a known tractor with plow attached and controlled by a hydraulic system embodying the features of the invention, the near rear wheel being omitted for the sake of clarity.

Fig. 2 is a sectional view taken longitudinally of the rear end of the tractor and showing on an enlarged scale a control system embodying the invention.

Fig. 3 is a sectional elevation to a further enlarged scale showing the valve arrangement of the system.

Figs. 4 and 5 are sectional views respectively on the lines 4—4 and 5—5 of Fig. 3.

Fig. 6 is a diagrammatic view of the hydraulic circuit.

Referring especially to Fig. 1, the tractor is of known type embodying the Ferguson System of a hitch linkage and an implement hydraulic control system operating on the principle set forth in said prior patents. The tractor comprises a body 1 and the usual rear ground wheels 2, the housing 1 and the usual rear ground wheels 2, the nearer wheel being omitted for clearness. The linkage system comprises an upper compression link 3 and two laterally spaced lower draft links 4, the links being triangularly spaced and universally attached to the tractor and implement. The tractor embodies a hydraulic system, described later, which operates two cranks 5 on the cross shaft 5A and serves to raise and lower the links 4 through the drop links 6A and thus raise and lower the implement. As shown, the implement is a plow but it may be any agricultural or other implement adapted to be attached to the links.

The known hydraulic system includes an oil ram consisting of a cylinder 6 to which oil under pressure can be supplied under control of valve means from a pump 20 which may comprise a piston or pistons 20A (Fig. 6) actuated by an eccentric or eccentrics 20B which are continuously driven by a shaft 20C from the tractor engine. The cylinder contains a ram or piston 7 connected to the crank 5. Admission of oil moves the piston to the right (as seen in Fig. 2) and raises the linkage while release of oil allows the implement to lower under its own weight. The system can be controlled both by the operator or automatically by the implement itself to maintain the implement at a predetermined depth. Briefly the control mechanism comprises a duplex "floating" lever 8, substantially similar to that disclosed in prior patent No. Re. 22,642, pivoted at 9 on the yoke or stirrup 10 connected to the rod 11 which in turn is connected to the top link 3 through a rocker or bell crank 3A. The upper end of the lever 8 is maintained by the tension spring 12 against an eccentric 13 which is under control of the control handle 14 (Figs. 1 and 2) actuatable by the operator. To raise the link (and an implement carried thereby) to the position shown in Fig. 2 the handle is moved to the position shown so as to move the eccentric 13 to rotate the lever clockwise about the pivot 9. This allows a valve means connected with the lower end of the lever 8 to be moved by spring 12 from its "neutral" position, in which the oil supply to the pump is cut off and the oil is trapped in the cylinder, to an intake position for admitting oil to the cylinder. The upward limit of lift is determined by projections 15 on the lever 8 which are engaged by the ram 7 as it moves out of the cylinder to rotate the lever 8 counterclockwise to cut off the supply of oil by moving the valve means back to its neutral position.

Automatic control of the depth is effected through the top link 3, rod 11 and yoke 10. If the implement goes too deep or too shallow the increased or decreased draft further compresses a balance spring 17 (arranged to resist inward movement of the rod 11) or allows it to expand and the lever 8 is swung clockwise or counterclockwise about its top end to cause admission or release of oil and raising or lowering of the implement. Such implement movement in turn reduces or increases the draft and causes the bal-

ance compression spring 17 to extend or be compressed and swing the lever 8 counterclockwise or clockwise until the valve means again reaches the neutral position. The above briefly described arrangement is well known, the valve means being arranged on the suction side of the pump to avoid continuous pumping of the oil.

A system embodying the present invention is shown diagrammatically in Fig. 6. A main control valve 21, which is responsive to variations in implement draft, is located in the delivery line 22 from the pump. A pressure fluid accumulator 26 is also in communication through line 22A with the line 22 on the pump side of the valve. The inlet port 23 to the pump, which is located on the suction side thereof, is controlled by a piston valve 24 which is under the opposed influence or control of a resilient resistant, such as a spring 25, and the pressure (through line 48) of the fluid in the pressure fluid accumulator 26. To this end, the valve 24 is engaged by a piston plunger 24A which constitutes a member connected so as to be continuously subjected to fluid at the pressure prevailing at the discharge side of the pump, the plunger 24A being slidable in a bore to which the line 48 is connected. The accumulator is, as mentioned above, connected to the delivery side 27 of the pump and also to the admission side 49 of the implement-controlled valve 21. It may consist of a device wherein the stored fluid is pressurized for subsequent delivery by entrapped air or by spring means. The pump has the usual inlet and outlet non-return valves 29, 30.

The actual construction of the arrangement is shown more clearly in Figs. 2 to 5. This construction uses the existing pump and associated casting 20D with its existing passages as at present in use on tractors sold under the trade-mark "Ferguson."

The duplex lever 8 is connected by links 31 to a fork 32 mounted between its ends to rock on a bracket 33 and pivotally connected at its lower end to a link 34 which is pivoted to the valve 21. The valve 21 in this instance comprises a central cylindrical part and two frusto-conical end parts (see Fig. 3), the central part cooperating with one or more radial ports 35 in a bushing 37 communicating with an annular chamber 36 which is connected by the conduit 38 (Figs. 2 and 6) with the cylinder 6. The valve has a tail-piece 39 thereon cooperating with the bushing 37 to define an annular transfer passage 39A which communicates through ports 40 with an annular chamber 41 which is connected to the pump delivery and the accumulator through the conduit 22 and distributor connection 22A.

The pump valve 24 is located below the valve 21 in a bushing 42 and is adapted to control a port 23 which is connected by a passage in the casting 20D to the pump through pump inlet valve 29 (see Fig. 6). The valve 24 has a plurality of openings 43 (Fig. 3) bored therein and the reduced diameter plunger 24A is attached thereto for sliding movement in a bore passage 44 in a plug 45 which is screwed into and closes one end of the bushing 42. Radial passages 46 connect the passage 44 with an annular chamber 47 which in turn is connected by the conduit 48 with the accumulator 26. The spring 25 bears against the end of the valve opposite the plunger 24A and against a pin 42A disposed crosswise of the bushing 42. The valve 24 is thus subject on the one end to the force of the pressure existing in the accumulator, which force is op-

posed by that of the compression spring 25. The valve is located in an oil sump 49. In the event the pressure in the accumulator falls below a predetermined value, the spring 25 will move the valve 24 to the right (as viewed in Figs. 2 and 3) to open port 23 and admit fluid through the open end of the bushing 42 to the intake valve 29 on the suction side of the pump. Ports 50 may be provided in the bushing to allow free movement of the valve and also to allow inflow of oil through the passages 43 into the port 23.

A stop 51 carried on the outer end of bushing 42 is provided to limit movement of the fork 32. To avoid breakage or undue stress in the lever 8, the latter in known fashion is formed of upper and lower parts adapted to "break" in jackknife fashion if it is rotated more than the stop 51 will allow.

The accumulator or pressurizing device 26 is of the well known type and need not be fully described. The form shown consists of a sphere containing a resilient diaphragm 52 dividing the sphere into an oil chamber 53 and an air-trap chamber 54 having a loaded air-admission valve 55 whereby any desired initial air pressure may be attained. An alternative known form may consist of a cylinder divided into oil and air chambers by a piston and a further known alternative may consist of an oil vessel containing a collapsible air sac.

With the arrangement herein shown and described, the continually-running pump 20 will deliver oil to the accumulator 26 past valve 30 and through lines 21, 22A and 48 until the pressure rise is sufficient to close valve 24 against the force of spring 25. The valve 24 is of course open whenever the line pressure is down. While the system is under accumulated pressure with both valves 24 and 21 closed, the pump will run idly under substantially no load, yet a supply of fluid under pressure will be available in chamber 39A at valve 21 for use the instant the valve 21 is opened. Whenever the line 38 to the ram is opened by movement of valve 21 from its illustrated neutral position (Fig. 6) to connect lines 22 and 38 through chamber 39A, the accumulated pressure fluid will supply the ram during the relatively brief lag preceding the delivery of fluid directly thereto from the pump. Such movement of the valve 21 will, of course, be in response to a shift of the control lever and linkage 8, 31, 32 which follows either the operation of the control system when the implement goes too deep and draft increases or a manual operation of the control system to raise the hitch links 4 and an implement thereon. Consequently, the system will be instantaneously actuated without lag. Moreover, there will be no over-delivery of fluid to the ram since when the valve 21 closes port 35 (as when the control system is automatically restored to its preset balanced condition or when the valve is moved to neutral by the engagement of lugs 15 on lever 8 by the end of the piston 7), the pump will then supply fluid to the accumulator until the pressure rise in that portion of the system closes valve 24 to prevent further delivery of fluid to the pump.

When the system is reversely actuated to exhaust fluid from the ram for lowering the hitch links and implement, the valve 21 is shifted to the left (Fig. 6) from its neutral position either automatically or manually. Fluid then flows from the ram through line 38 and the right-hand end of bushing 37. The accumulated pressure fluid remains available since the portion of

the system in which it is stored is not affected by the movement of the valve 21 to exhaust fluid from the ram. It will be noted that the accumulator system will replenish automatically any incidental leakage since resulting pressure loss therein will allow valve 24 to move and open the pump supply line.

It will also be understood that the accumulator system may be used to provide an immediately available supply of pressurized oil, for example, through a branch conduit 48A (Fig. 6) for actuation of auxiliary devices, for instance, for lifting and lowering an implement mounted at the front of the tractor and which may be subject to automatic depth control as above described.

The capacity of the accumulator and the pressure on the fluid in that system may be varied in accordance with requirements and it will be understood that in some cases there need be no especially large accumulator vessel, the minimum requirement being a pressurizing device between the pump delivery and the implement controlled valve which has sufficient capacity to deliver enough pressurized fluid to maintain an actuating pressure until the pump has filled and is effectively delivering the oil.

It is to be understood that the above more specific embodiments have been described merely by way of example and that modification may be made without departing from the scope of the invention.

In the event of the implement striking an obstruction, the consequently excessive movement of the lever 8 swings the projections 15 into contact with the cylinder 6 so that the swinging movement of the lever is reversed to an anti-clockwise movement as disclosed in said prior Patent No. Re. 22,642. The valve 21 is thus moved to the left to allow discharge of oil from the cylinder 6, through the ports 35 and the right-hand end of the bushing 37 into the sump 49. Thus the present invention admits of the overload release effect as disclosed in the prior Patents Nos. 2,118,181 and Re. 22,642.

The invention is also applicable to hydraulic systems wherein the implement automatically controls the system to maintain the implement in a predetermined position with reference to the tractor as distinct from the above-described load or depth control. An example of such system is disclosed in a copending application filed by Ernest V. Bunting, Serial No. 712,125, now Patent No. 2,632,628.

We claim as our invention:

1. A hydraulic control system for an agricultural tractor or the like which comprises the combination of a fluid-operable actuating or load-sustaining device for a soil-engaging or agricultural implement which is to be controlled, valve means movable progressively to admit fluid to or release it from said device at a rate proportioned to the degree of movement thereof to correctively restore said implement to a predetermined depth or draft, and a source of pressurized fluid for actuating said load-sustaining device which includes a container for pressure fluid, a continuously driven pump, connections between said container, the discharge side of said pump and said valve means for supplying fluid from said pump to said container and said device simultaneously, or for supplying pressure fluid to the device from the container and pump simultaneously, and control means on the admission side of the pump responsive to the pressure

of the fluid in said container to put the pump automatically into or out of effective operation to maintain the fluid at a predetermined pressure in said container.

2. In a hydraulic system for effecting an accurately proportioned response to displacement of a control member, the combination of a continuously driven pump, a single acting hydraulic actuator operable against a load by fluid supplied from said pump, a first control valve interposed between said actuator and the discharge of said pump, said valve having relatively slideable plunger and housing elements with a port in the latter connected to said actuator, said elements being operatively associated with the displaceable control member and relatively slideable thereby from a neutral position, in which said plunger substantially blocks said port, in opposite directions from such neutral position to open said port respectively to the discharge of said pump and to drain and with a progressive opening of said port in each direction, a second control valve arranged to open and close the intake of said pump, said second control valve being spring biased to open position, and a fluid pressure operated member connected so as to be continuously subjected to fluid at the pressure prevailing at the discharge side of said pump and mechanically connected to said second control valve to close the latter against the influence of its spring bias in response to the establishment of a predetermined pressure head at the discharge side of the pump irrespective of the position of the first control valve.

3. A system as set forth in claim 1, in which means is provided for supplying fluid out of the system to an auxiliary actuator or the like from a point intermediate said valve means and the discharge of said pump.

4. In a hydraulic control system for a tractor having a trailing implement hitch, a single acting hydraulic actuator for raising and lowering the hitch with an implement attached thereto

5 10 15 20 25 30 35 40

and a control member displaceable in proportion to the draft load on the hitch, the combination of a continuously driven pump connected for supplying fluid under pressure to the actuator, a first control valve interposed between said actuator and the discharge of said pump, said valve having relatively slideable plunger and housing elements with a port in the latter connected to the actuator, said elements being operatively associated with the displaceable control member and relatively slideable thereby from a neutral position, in which said plunger substantially blocks said port, in opposite directions from such neutral position to open said port respectively to the discharge of said pump and to drain and with a progressive opening of said port in each direction, a second control valve arranged to open and close the intake of said pump, said second control valve being spring biased to open position, and a fluid pressure operated member connected so as to be continuously subjected to fluid at the pressure prevailing at the discharge side of said pump and mechanically connected to said second control valve to close the latter against the influence of its spring bias in response to the establishment of a predetermined pressure head at the discharge side of the pump, irrespective of the position of the first control valve.
